SAFETY CIRCUIT CUT-OUT.

Application filed August 24, 1921. Serial No. 494,823.

(GRANTED UNDER THE PROVISIONS OF THE ACT OF MARCH 3, 1921, 41 STAT. L., 1313.)

To all whom it may concern:

Be it known that I, MARTIN HÖCHSTÄDTER, a citizen of the German Empire, residing at 's Gravenhage, Netherlands, have 5 invented certain new and useful Improvements in Safety Circuit Cut-Outs (for which I have filed applications in Netherlands May 17th, 1920, Ser. No. 14,830; Germany, filed May 22nd, 1920, Ser. No. 81,083), 10 of which the following is a specification.

Safety apparatus for the automatic disconnection of faulty sections of electric supply circuits are known wherein auxiliary lines are arranged parallel to the main lines 15 and connected at the ends of the sections through transformers to the main lines. The transformers are so dimensioned and connected relatively together as to generate a shifting of potential, whilst leaving the 20 auxiliary line still carrying the current of the supply circuit.

In the normal working of the supply circuit, the transformers produce a state of equilibrium in the two lines so that therefore the ratio between the currents in the 25 main line and the auxiliary line is constant for all loads.

If this ratio is varied by the occurrence 30 of a fault, differential relays that are included in the line circuits, come into operation and cut out the faulty section.

In the aforesaid known apparatus it is 35 essential that the two transformers of one section shall be different from each other. The manner in which this difference is to be selected in order to produce the most favourable conditions, is the object of the present invention.

This present invention provides an improved means for keeping constant the ratio 40 between the effective values of the currents in the two conductors from a low working current up to the greatest overload. This improved means consists in making transforming ratio of at least one of the two coupling transformers of the line section smaller than the impedance ratio between the main line and the auxiliary line.

Some practical embodiments of this invention are illustrated in the accompanying drawings, in which—

Fig. 1 illustrates the connection of the transformers of the safety apparatus;

Fig. 2 illustrates a scheme of connections of the improved apparatus wherein the primary windings of both transformers carry the undivided current; 55

Fig. 3 illustrates another modification in which the primary of one transformer carries the divided current whereas the primary winding of the other transformer carries the undivided current; 60

Fig. 4 illustrates a line section arranged similar to that shown in Fig. 1, but having two transformers of different size core; and 65

Fig. 5 illustrates an arrangement also similar to Fig. 1 but having resistances arranged in parallel to the transformer windings.

In Fig. 1 the current flows from the 70 switch 11 to the branching-off point 17 and thence in one direction through the primary winding 13 line section 1, primary winding 23 and the branching-off point 27 to the switch 22; and in another direction 75 from the branching-off point 17 through the secondary winding 14, branch line 2, secondary winding 24 to the branching-off point 27 and thence to the switch 22. The secondary windings 14 and 24 are connected 80 in the opposite way. In this connection therefore both primary windings carry only one branch current.

Switches 11 and 22 are operated by differential relays which receive their current 85 from transformers at their respective end of the section. For this purpose for instance the right hand end of the section is provided with three differential relay coils 33, two of which are located in the main or auxiliary line respectively, the third being inductively connected with the first two and in circuit with tripping coil 35. This coil may operate cut-out switch 11 in any conventional manner known in the art. 90

The other end of the line section is correspondingly provided with differential coils 32 and tripping coil 34. The cut-out switches 11 and 22 shown in the remaining figures to be described presently, may be 100 similarly actuated, as shown.

In order to assure that the transformers shall give a determined voltage, for instance two hundred volts, even when there is only a very small working current flowing in the 105 line sections, and to assure that this voltage,

in the case of full load and even so great 5 overload, shall not appreciably increase or at least shall not exceed a determined value, the transformers are constructed in such a manner that their iron cores shall become magnetically saturated even with a very low working current (5 to 10 per cent). It is 10 advisable to give to both transformers a smaller transforming ratio than the impedance ratio between the main line and the auxiliary line but it is necessary that this be the case at least for one of the two 15 transformers.

By "transforming ratio" of the 20 transformers I mean to imply the ratio of the number of its turns located in the auxiliary line to the number of turns of its coil located in the main line. The following may 25 serve as an example of how for instance the transformer arrangement illustrated in Figure 1 may be executed in practice in so far as the transforming ratio and the impedance ratio above referred to is concerned.

Assuming that the cross sectional area of 30 the main line be 30 times that of the auxiliary line area, then the impedance ratio between the auxiliary line and the main line has the value 30. Then in a transformer arrangement such as is shown in Figure 1 35 the following ratios of the transformers may be chosen.

Right hand or "first" transformer.

Primary winding (13)-----12 turns
Secondary winding (14)-----81 turns

Left hand or "second" transformer.

Primary winding (23)-----6 turns
Secondary winding (24)-----99 turns

40 Thus the ratio of the "first" transformer is

$$\frac{81}{12} = 6.75,$$

45 which value is indeed smaller than 15 or one-half of the impedance ratio between the auxiliary and main line. Furthermore, the number of turns, 6, of the primary winding 23 of the second transformer is smaller 50 than the number of turns, 12, of the primary winding 13 of the first transformer. On the other hand, the number of turns, 99, of the secondary winding 24 of the second transformer is greater than the number of 55 turns, 81, of the secondary winding 14 of the first transformer.

The result of the improved arrangement 60 is that a constant voltage is generated between the main line and the auxiliary line at all points of the line section and at all loads; and that the normal current ratio between the two branches of the line is approximately maintained in spite of the included transformers, just as would have been 65 the case without the transformers. Fur-

ther, the two currents remain almost completely in phase with each other. The equilibrium between the currents in the main line and the auxiliary line is extraordinarily stable and the differential relays can be 70 given a high degree of sensitiveness. The conditions of the apparatus illustrated in Fig. 1 are rendered particularly favourable as regards the equilibrium between the two lines and the absence of shifting of phase 75 in the auxiliary line relatively to the current in the main line, by making the transforming ratio of the first transformer of one line section smaller than the half of the impedance ratio of the two lines, and further by giving 80 to the section transformer, whose secondary winding is connected in the reverse way to the secondary winding of the first transformer, a smaller number of primary winding turns and a larger number of secondary 85 winding turns than to the first transformer. By the distinctive designation "first" transformer and "second" transformer, used hereinafter and in the annexed claims, I mean to 90 imply a distinction between the two transformers, in so far as in the actual connection of the two transformers in one line section, the iron core of the first transformer is magnetized by its two coils in different senses, whereas the iron core of the second transformer is magnetized by these two coils 95 in the same sense. These designations thus refer solely to the actual additions of magnetization in the transformers themselves, and are independent of the direction of the 100 transmission of energy in the line section, that is to say it is immaterial at which end of the line section the "first" or "second" transformer is situated.

By this improved arrangement, the same 105 magnetic conditions are produced in the first and second transformers of a line section at all loads. The improved apparatus ensures an exact equalization, and has very great 110 practical advantages, for instance the releasing devices (relays) may be adjusted with extraordinary sensitiveness because in the normal working, not only the ratio between the effective values of the currents, but also 115 the forms and relative positions of the curves of the main current and auxiliary current are invariable for all load conditions. Instead of making the number of primary turns of the two transformers different from each other, the dimensions of the iron of 120 the two transformers may be made correspondingly different, or both means may be combined together. Incidentally the saturation of the transformers has also the advantage that according to experience, such 125 saturated transformers offer to the high frequency waves and impact waves that traverse the line, a smaller resistance than unsaturated iron devices. An exact equalization 130 of the two transformers of one line section

5 relatively to each other and to the impedance ratio between the main line and the auxiliary line, may also be produced by the following constructional forms which offer 10 constructional advantages.

10 The operation of the apparatus shown in Fig. 2 is the same as that in Fig. 1, except that the winding ratios of the transformers must be calculated differently. Of course, 15 the iron relations may also be varied; but in the following description for the sake of simplicity, it is assumed that the iron dimensions of both transformers are the same. If the iron cores 15 and 25 are equal, the two 20 secondary windings 14 and 24 will have equal numbers of turns. The number of primary turns in the second transformer 23, 24, 25 must again, as above, be smaller than the number of primary turns in the first 25 transformer 13, 14, 15. By reason of the fact however, that the secondary windings of the two transformers must not be made different from each other, but are given the same number of turns, an advantage is gained for the mass production of certain types of transformers.

Fig. 3 illustrates another modification 30 wherein the primary winding 13 of the transformer 13, 14, 15 carries the divided current, whereas the primary winding 23 of transformer 23, 24, 25 carries the undivided current. The branching-off point 35 17 for the line 2 is situated, in the case of transformer 13, 14, 15 between the switch 11 and the primary winding 13, whereas the branching-off point 26, in the case of the other transformer, is situated between the two primary windings. This arrangement 40 no doubt loses the advantage of equal numbers of turns of secondary windings. They must be made different from one another in such a manner that the number of turns of the coil 24 of the second transformer is equal to the sum of the numbers of turns 45 of coils 13 and 14. This modification is advantageous inasmuch as that with otherwise equal conditions, the number of turns of the coil 24 is rather smaller than in the case of modification shown in Fig. 1. It 50 is also possible to employ for the transformers iron cores of different dimensions, or to allow of using a plurality of transformers at each end of the line section; each 55 transformer being subdivided into a plurality of transformers or being provided with a plurality of iron cores as desired. In this case, however, at least two transformers 60 of one line section must be different from each other, and they must be constructed with different iron cores, so long as by correct selection of the numbers of turns in 65 proportion to the iron cores and in proportion to the impedance of the main line of the auxiliary line, care is taken that the magnetic induction in the iron cores is al-

ways the same. These conditions can be calculated in advance.

Fig. 4 illustrates an arrangement of this kind. The secondary coils 14 and 24 which are connected to the branching-off points 17 70 and 27 of the main line section 1, are again connected in opposite ways. As before, the problem consists in so constructing these transformers that the most uniform possible voltage shall be generated at points of the 75 line section between the parallel lines 1 and 2, and that, nevertheless, the normal distribution of a current between the main line and the auxiliary line shall be maintained for all loads on the line section. Further, all shifting of phase and distortion of the two coils in the lines 1 and 2 relatively to each other shall be avoided as far as possible. That is to say, in normal working the transformers must generate a difference of potential between the main line and the auxiliary line without exerting any appreciable influence upon the current flowing through the said lines. Assuming the case where it is desired to protect a line 80 carrying very large current; the main line and the auxiliary line will therefore be very unequal, so that the auxiliary line will carry only a comparatively weak branch current. In this case it is advisable to mount 85 the transformers directly upon the conductor bars or upon a conducting tube. This is illustrated in Fig. 4 where the iron cores 15 and 25 consist of rings which are simply slipped on to the line portions 13 and 23, 90 and carry the secondary windings 14 and 24. In order to produce the desired state of equilibrium between the main line and the auxiliary line with the use of only one primary winding for each, the iron rings of 95 the transformers must have different diameters because the desired equilibrium cannot be attained solely by the choice of the turns in proportion to the impedance ratio between the lines or by varying the cross-sections of 100 the iron. The requisite length of the path of the lines of force in both iron cores can be calculated in advance in connection with the impedance ratio between the main line and the auxiliary line and the numbers of 105 winding turns of the transformers, and the cross-sections of the iron.

110 The arrangement shown in Fig. 4 is particularly adapted for building up the transformers out of part transformers by slipping a plurality of iron rings on to the common conducting tube 13 or 23. The rings may be provided either singly or in common with the secondary windings. In this way transformers can be built up 115 from a small number of existing patterns in a simple manner for the various lengths of line and current. The improved apparatus particularly advantageously permits of a 120 great freedom of design of the transformers 125 130

and their electrical connections, nevertheless, owing to the equal magnetic induction, the ratio of the currents in the parallel lines, is maintained perfectly independent of 5 the condition of load on the line section. Thus it is possible to adapt to a very full extent the construction of the transformers to the existing electrical and space conditions. For practical working it may be advisable 10 to bridge the transformers of one or both sides with ohmic or capacity resistances. By building-in the resistances care must be taken of course not to interfere with the equilibrium of the currents in the main line 15 and auxiliary line, and not to diminish the sensitiveness of the apparatus as regards disconnection in the case of a fault.

Fig. 5 illustrates the connections. The resistance 28 is connected in parallel with 2 the primary winding 13 and resistance 29 is connected in parallel with the secondary winding 14. The resistances 30 and 31 are connected in parallel with the coils 23 and 24 of the other transformer. Comparatively 20 very small ohmic values can be employed for the primary and secondary resistances. Likewise the primary ohmic values may be chosen fairly independently of the secondary ohmic values. However the ratio of the 25 two primary ohmic values to the two secondary ohmic values must be the same as the ratio of the windings to which they are connected in parallel. Thus, for example, if the second transformer has one half the 30 number of primary winding turns and twenty per cent more secondary windings than the first transformer, then this primary 35 parallel resistance must be equal to one half the ohmic value of that of the primary resistance of the first transformer, and its secondary resistance must have an ohmic value twenty per cent higher than that of the secondary resistance of the first transformer.

45 What I claim is:—

1. In an automatic safety circuit cut-out system for line sections of the character described, having a main line and an auxiliary line in each line section and transformers at the ends of each line section for coupling the auxiliary line to the main line, and adapted to cause the cut-out operation in case of line disturbance, the transformer ratio of at least one of said coupling transformers being smaller than the impedance ratio between the main and the auxiliary line.

2. In an automatic safety circuit cut-out system for line sections of the character described, having a main line and an auxiliary line in each line section and transformers at the ends of each line section for coupling the auxiliary line to the main line, and adapted to cause the cut-out operation 60 in case of line disturbance, the transformer

ratio of at least one of said coupling transformers being smaller than the impedance ratio between the main and the auxiliary line, said transformers being suitably dimensioned and connected to each other 70 to have magnetic saturation at normal working currents in the section.

3. In an automatic safety circuit cut-out system for line sections of the character described, having a main line and an auxiliary line in each line section and transformers at the ends of each line section for coupling the auxiliary line to the main line, and adapted to cause the cut-out operation 75 in case of line disturbance, the transformer ratio of at least one of said coupling transformers being smaller than the impedance ratio between the main and the auxiliary line, the "first" transformer of each line section having its primary and secondary 80 windings arranged to produce opposing magnetic fields and having the transformation ratio between its windings smaller than one-half of the impedance ratio between the main and the auxiliary line section.

4. In an automatic safety circuit cut-out system for line sections of the character described, having a main line and an auxiliary line in each line section and transformers at the ends of each line section for coupling the auxiliary line to the main line, and adapted to cause the cut-out operation in case of line disturbance, the transformer ratio of at least 85 one of said coupling transformers being smaller than the impedance ratio between the main and the auxiliary line, the "second" transformer of each line section having a smaller number of primary windings than the "first" transformer, and a number of secondary windings larger than the number of secondary windings of the "first" transformer.

5. In an automatic safety circuit cut-out system for line sections of the character described, having a main line and an auxiliary line in each line section and transformers at the ends of each line section for coupling the auxiliary line to the main line, and adapted to cause the cut-out operation in case of line disturbance, the transformer ratio of at least 90 one of said coupling transformers being smaller than the impedance ratio between the main and the auxiliary line, the "second" transformer of each line section having a smaller number of primary windings than the "first" transformer, and a number of secondary windings equal to the sum of the number of secondary and primary windings of the "first" transformer.

6. In an automatic safety circuit cut-out system for line sections of the character described, having a main line and an auxiliary line in each line section and transformers at the ends of each line section for coupling 95 the auxiliary line to the main line, and

- adapted to cause the cut-out operation in case of line disturbance, the transformer ratio of at least one of said coupling transformers being smaller than the impedance ratio between the main and the auxiliary line, at least one of said transformers being built up of a plurality of part transformers, at least two of each part transformers of a line section being different from each other.
- 19 7. In an automatic safety circuit cut-out system for line sections of the character described, having a main line and an auxiliary line in each line section and transformers at the ends of each line section for coupling

the auxiliary line to the main line, and 15 adapted to cause the cut-out operation in case of line disturbance, the transformer ratio of at least one of said coupling transformers being smaller than the impedance ratio between the main and the auxiliary 20 line, and resistances disposed in shunt to the windings of said transformers, the ratio of the ohmic values of the two primary resistances to the secondary resistances being the same as the ratio of the windings to which 25 they are shunted.

In testimony whereof I affix my signature.

MARTIN HÖCHSTÄDTER.
